(57) **CLAIM**

The ornamental design for a respirator cartridge body, as shown and described.

DESCRIPTION

FIG. 1 is a perspective view showing the new design for a respirator cartridge body.

FIG. 2 is a front view thereof;

FIG. 3 is a rear view thereof;

FIG. 4 is a top view thereof, the bottom being a mirror image thereof;

FIG. 5 is a left side view thereof; and,

FIG. 6 is a right side view thereof.

The broken lines in the drawings illustrate portions of the respirator cartridge body which form no part of the claimed design.

1 Claim, 3 Drawing Sheets
